UNITED STATES PATENT OFFICE.

HARRY T. ANDERSON, OF BUTLER, PENNSYLVANIA, ASSIGNOR TO STANDARD STEEL
CAR CO., OF PITTSBURGH, PENNSYLVANIA, A CORPORATION OF PENNSYLVANIA.

DOOR-OPERATING MECHANISM.

1,064,879.

Specification of Letters Patent. Patented June 17, 1913.

Application filed February 23, 1912. Serial No. 679,316.

To all whom it may concern:

Be it known that I, HARRY T. ANDERSON, a citizen of the United States, and resident of Butler, in the county of Butler and State 5 of Pennsylvania, have invented a new and useful Improvement in Door-Operating Mechanism; and I do hereby declare the following to be a full, clear, and exact description thereof.

10 My invention relates to door-operating mechanism.

This invention relates more particularly to that class of door-operating mechanism in which a movable latch is carried by the door 15 at the outer end with a winding chain connected to said latch, the latch will be drawn forward and supported by the winding shaft, when the door is closed, so as to relieve the weight on the chain and support 20 the door directly on the shaft.

The object of my present invention is to improve this form of door operating mechanism as heretofore constructed in certain ways, and to these ends my invention comprises the novel features herein set forth and 25 claimed.

In the drawings Figure 1 is a plan view of a portion of a bottom of a car showing my invention applied thereto; Fig. 2 is an 30 enlarged section on the line 2—2 Fig. 1; Fig. 3 is a sectional view showing the door closed and the dotted lines showing the door in the open position; and Figs. 4 and 5 are enlarged details.

35 In the drawing the numeral 2 designates the bottom of a suitable car provided with openings closed by the doors 3. These doors may be arranged in pairs on each side of the center sill of the car, said doors being 40 hinged by suitable hinges 5 to the car-body. Each door is provided with one or more movable latch-members 6. These latch-members are adapted to move back and forth in the casing 7. This casing may be 45 formed of wrought metal and is riveted or otherwise secured to the outer end of the door 3. The latch-member 6 may be formed of cast-metal and at its rear end it is supported within the casing 7 upon the roller 50 8 which rests on the bottom plate 7a. The bolt 9 forms a stop for the roller and controls the outward movement of the latch-member 6. The outer end of the latch-member 6 is bifurcated to form the two arms 10

and 11 with the space 12 between the same. These bifurcated ends project out beyond the door. 55

The chains 13 are secured to the latch-members 6, one of the links of said chain having the threaded shank 14 which passes 60 through the lug 15 on the latch-member and a nut 16 is screwed onto said threaded shank to secure same to said latch-member.

A roller 17 is interposed between the upper face of the latch-member and the door to 65 provide for the easy movement of the latch-member in moving in and out.

The casing 7 is provided with the lower bottom plate 18 and the opening 19 to permit of the backward movement of the latch-member without interference. 70

The chain 13 passes around the shaft 20 and said shaft is provided with the U-shaped kicker 21 which extends beyond the circumference of the shaft so as to engage the outer 75 end of the latch-member, or one of the arms 12 thereof. The other end of the chain 13 is secured to the shaft 20.

When my improved door-operating mechanism is in use and the door is closed, the 80 parts will be in the position indicated in full lines Figs. 3 and 4 with the latch-member 6 resting on the shaft 20. When it is desired to open the door, the operator turns the shaft 20 which is provided at one end 85 with a suitable ratchet and pawl mechanism 22. A suitable wrench may be applied to the outer end of the shaft 20 for the purpose of turning the same. As the shaft 20 is turned the kicker 21 will engage the outer 90 ends of the latch-member 6 and will move said latch members rearwardly until said latch members are moved back off the shaft 20 whereupon the weight of the contents of the car acting on the doors will cause the 95 doors to swing downwardly into position indicated in Fig. 3 the contents of the car being discharged in this manner. The latch-members themselves will assume the position indicated in dotted lines Fig. 3 and be 100 held in this position by the chains 13. When it is desired to close the door the shaft 21 is turned and the chain wound up on said shaft and as the latch-member comes in contact with the shaft 20 the bevel ends 24 of said 105 latch-members will engage the lower side of the shaft, and upon the further movement of the shaft the latch-members will be forced

backward to clear the shaft, and upon the continued rotation of the shaft the chains will draw the latch-members outward until they rest upon the shaft 20 as indicated in 5 Fig. 4. By having the latch-members mounted on the rollers in this manner the movement of the latch-members is accomplished with very little friction, so that the power to move the latch members forward 10 to engage the shafts 20 is reduced to a minimum, and the latch-members rest directly upon the shaft when the door is closed thereby relieving the chain of all stress. The releasing of the latch-members from the shaft 15 20 is accomplished by a slight rotation of the shaft and the friction rollers relieve the resistance to the backward movement of the latch-members, so that very little power is required to rotate the shaft 20 sufficiently to 20 move the latch-members by the kickers 21.

While I have illustrated my invention in connection with a shaft running transversely of the car, it is apparent that the device is equally practicable to a shaft running longitudinally of the car where the 25

doors swing in a direction at right angles to that illustrated.

What I claim is:

In door-operating mechanism, the combination with a car-body, of a downwardly 30 swinging door, a casing secured to the lower side of said door, said casing having bottoms at different levels with an opening formed between same, a movable latch-member in said casing, a roller interposed 35 between said latch-member and the upper bottom of said casing, a roller interposed between the upper face of said latch-member and the lower face of said door, a winding-shaft upon which said latch-member rests, a 40 chain connected to said latch-member, and means carried by said shaft for moving said latch-member backward.

In testimony whereof, I the said HARRY T. ANDERSON have hereunto set my hand.

HARRY T. ANDERSON.
